(57) **CLAIM**

I claim the ornamental design for a wearable stimulation device, as shown and described.

DESCRIPTION

FIG. 1 is a perspective view of an embodiment of the claimed design;

FIG. 2 is a front view of the claimed design shown in FIG. 1;

FIG. 3 is a rear view of the claimed design shown in FIG. 1;

FIG. 4 is a left side view of the claimed design shown in FIG. 1;

FIG. 5 is a right side view of the claimed design shown in FIG. 1;

FIG. 6 is a bottom view of the claimed design shown in FIG. 1; and,

FIG. 7 is a top view of the claimed design shown in FIG. 1. The ornamental design that is claimed is shown in the drawings as solid lines and surfaces having surface shading.
